UNITED STATES PATENT OFFICE.

MARCELLUS R. BENNETT, OF WILKES-BARRE, PENNSYLVANIA.

AIR-VALVE FOR INTERNAL-COMBUSTION ENGINES.

1,113,867.

Specification of Letters Patent.

Patented Oct. 13, 1914.

Application filed January 17, 1914. Serial No. 812,782.

To all whom it may concern:

Be it known that I, MARCELLUS R. BENNETT, a citizen of the United States, residing at Wilkes-Barre, in the county of Luzerne and State of Pennsylvania, have invented new and useful Improvements in Air-Valves for Internal-Combustion Engines, of which the following is a specification.

This invention relates to improvements in air valves for internal combustion engines and has particular application to a valve whereby air may be admitted to the gas intake pipe of the engine in any desired quantity or volume.

In carrying out the present invention, it is my purpose to provide an air valve which will be manually controlled and whereby any desired volume of air may be drawn into the gas intake pipe of the engine between the manifold and the carbureter and whereby any pressure due to back firing will be automatically relieved.

It is also my purpose to provide a valve of the class described which will be constructed in such manner that the air will be drawn into the gas inlet pipe in the form of streams thereby breaking up the gas passing through the supply pipe and into the manifold and commingling therewith.

Furthermore, I aim to provide a valve of the type set forth whereby the air drawn into the gas inlet pipe will be in the form of streams and maintain its force, incident to the stream formation, for a relatively long time, thereby effectively commingling with the gas passing through the pipe and breaking up the same with the result that an efficient combustible mixture is produced with a minimum consumption of liquid fuel.

With the above and other objects in view, the invention consists in the construction, combination and arrangement of parts hereinafter set forth in and falling within the scope of the claims.

In the accompanying drawings: Figure 1 is a view in side elevation of an internal combustion engine equipped with an air controlling valve constructed in accordance with the present invention. Fig. 2 is a transverse sectional view through the gas intake pipe showing the valve structure on an enlarged scale. Fig. 3 is a view in side elevation of the valve removed from the pipe. Fig. 4 is an enlarged vertical sectional view therethrough. Fig. 5 is a transverse sectional view on the line 5—5 of Fig. 4.

Referring now to the drawings in detail, 1 designates the carbureter or vaporizer of an internal combustion engine, while 2 indicates the manifold connected with the cylinders and 3 the gas supply pipe connecting the carbureter with the manifold.

Located in the supply pipe 3 and designed to admit air thereto is my improved air regulating valve, such valve comprising, in present instance, a cylindrical sleeve 4 threaded into an opening in the supply pipe 3 at a suitable distance above the carbureter. Arranged within the sleeve 4 longitudinally thereof is a series of tubes 5 opening into the supply pipe 3 and having the outer ends thereof flush with the outer edge of the sleeve 4. Threaded onto the outer end of the sleeve 4 is a collar 6 preferably of non-circular contour, while secured to the collar is a plate 7 having an opening formed therein registering with the sleeve 4. Projecting outwardly from the plate 7 above the connection between the plate and sleeve is a pivot pin 8 and pivotally mounted upon such pin is a closure in the form of a plate 9 lying in face to face contact with the plate 7 and designed to close the outer ends of the tubes within the sleeve 4. Projecting outwardly from the outer face of the closure plate 9 and registering with the sleeve 4 is a cylindrical valve casing 10 coaxial with the sleeve 4 and arranged within the valve casing 10 is a valve disk 11 constructed of fiber or other suitable material and provided with a stem 12 extending into the casing 10. Surrounding the stem 12 is a coiled expansion spring 13 having one end abutting the disk and the opposite extremity in engagement with the end wall of the valve casing 10, such spring holding the valve disk in frictional engagement with the outer end of the sleeve 4, such end of the sleeve constituting a seat for the disk when the closure plate is in closed position. The outer end of the pivot pin 8 is equipped with a head 14 spaced apart from the outer face of the closure plate 9 and encircling the projecting end of the pin is a coiled expansion spring 15 abutting the confronting portions of the head 14 and the plate 10 acting to hold the confronting faces of the closure plate and the plate 7 in frictional engagement and permitting movement of the closure plate about the pivot pin to uncover the outer ends of the tubes 5 within the sleeve 4 so

that air may be admitted to the supply pipe. Connected with the closure plate and extending at right angles thereto is an arm 16 connected through the medium of a rod or the like with an operating lever located upon the steering wheel or dash board of the vehicle. In the present instance, one end of the spring 15 is secured to the arm 16, while the opposite end bears against one edge of the closure plate so as to hold such plate normally in closed position and return the same to such position upon the release of the arm 16.

From the foregoing description taken in connection with the accompanying drawings, the construction, mode of operation and manner of employing my invention will be readily apparent.

Assuming the air regulating valve to be installed as illustrated in Figs. 1 and 2, the operator of the vehicle manipulates the respective lever and so causes the arm 16 to swing the closure plate 9 about the pivot pin 8 and against the action of the restoring spring thereby uncovering the outer ends of the tube 5. As the outer ends of the tubes are uncovered, the air rushes into the gas supply pipe 3, incident to the suction created in such pipe in the operation of the engine. It will be noted that the air passing through the tubes 5 is projected into the gas supply pipe in the form of jets or streams thereby increasing the force of the air and effectively breaking up the gas passing to the manifold and commingling therewith so that a highly combustible mixture is produced with a minimum consumption of gasoline. It will be seen that any number of tubes 5 may be brought into service independently of the remaining tubes thereby permitting the volume of air passing through the regulating valve to be regulated in accordance with the speed of the engine.

When the closure plate is in closed position, the valve disk 11 seats upon the outer end of the sleeve 4 and is held against such seat by means of the spring 13 thereby effectively closing the outer ends of the tubes 5.

Should the engine "back fire", the pressure thus set up will cause the valve disk 11 to disengage the seat against the action of the spring 13 thereby relieving such pressure.

While I have herein shown and described one preferred form of my invention by way of illustration, I wish it to be understood that I do not limit or confine myself to the precise details of construction herein described and delineated, as modification and variation may be made within the scope of the claims without departing from the spirit of the invention. For instance, a metallic plug having a series of longitudinal pas-

sages therein may be substituted for the plurality of tubes within the sleeve, or any other structure may be utilized, in place of the tubes within the sleeve, which is capable of delivering air to the intake pipe or manifold in individual jets or streams.

I claim:

1. The combination with the intake pipe of an internal combustion engine, of an air supply valve in said pipe comprising a series of tubes arranged side by side and opening into said pipe, and a closure covering the outer ends of said tubes and movable over the same whereby any number of said tubes may be uncovered to vary the volume of air flowing into the manifold in accordance with the speed of the engine.

2. The combination with the intake pipe of an internal combustion engine, of an air supply valve in said pipe comprising a series of tubes arranged side by side and opening into said pipe, a closure plate covering the outer ends of said tubes and movable over the same whereby any number of said tubes may be uncovered, means for swinging said plate, and means for restoring said plate to normal position.

3. The combination with the intake pipe of an internal combustion engine, of an air supply valve in said pipe comprising a series of tubes arranged side by side and opening into said pipe, a closure plate covering the outer ends of said tubes and movable over the same whereby any number of said tubes may be uncovered, means for swinging said plate, and a spring for restoring said plate to normal position.

4. The combination with the intake pipe of an internal combustion engine, of an air supply valve in said pipe comprising a series of tubes arranged side by side and opening into said pipe, a sleeve surrounding said tubes, a plate connected to the outer end of said sleeve and having an opening therein coaxial with the sleeve, and a closure plate pivoted upon said first plate and normally closing the outer ends of said tubes.

5. The combination with the intake pipe of an internal combustion engine, of an air supply valve in said pipe comprising a series of tubes arranged side by side and opening into said pipe, a sleeve surrounding said tubes, a plate connected to the outer end of said sleeve and having an opening therein coaxial with the sleeve, a closure plate pivoted upon said first plate and normally closing the outer ends of said tubes, and means for swinging said closure plate to uncover the outer ends of said tubes.

6. The combination with the intake pipe of an internal combustion engine, of an air supply valve in said pipe comprising a series of tubes arranged side by side and opening into said pipe, a sleeve surrounding

said tubes; a plate connected to the outer end of said sleeve and having an opening therein coaxial with the sleeve, a closure plate pivoted upon said first plate and normally closing the outer ends of said tubes, means for swinging said closure plate to uncover the outer ends of said tubes, and a spring for restoring said plate to closed position.

7. The combination with the intake pipe 10 of an internal combustion engine, of an air supply valve in said pipe comprising a series of tubes arranged side by side and opening into said pipe, a valve disk closing the outer ends of said tubes and designed to 15 open the tubes in the event of back pressure, and means for sliding said valve disk to uncover said tubes.

8. The combination with the intake pipe 20 of an internal combustion engine, of an air supply valve in said pipe comprising a cylindrical sleeve, tubes within said sleeve and

arranged longitudinally thereof and having the inner ends thereof opening into the supply pipe and the outer extremities flush with the outer edge of the sleeve, a plate secured to said sleeve and having an opening therein registering with the sleeve, a pivot pin carried by said plate above the connection between the latter and the sleeve, a closure plate pivoted upon said pin and lying in face to face contact with said first plate and normally closing the outer ends of the tubes within the sleeve, and a coiled expansion spring encircling said pivot pin and holding said second named plate normally in closed position.

In testimony whereof I affix my signature in presence of two witnesses.

MARCELLUS R. BENNETT.
